UNITED STATES PATENT OFFICE.

CHRISTINE PETERSEN, OF EVANSTON, ILLINOIS.

BRASSIÈRE.

Application filed March 6, 1923, Serial No. 623,158. Renewed March 23, 1926.

This invention relates to brassières for ladies' wear, and has for its object to provide an improved brassière which can be quickly put on or taken off and which is provided with improved means for retaining it in position. Ordinary brassières have a tendency to slip up above the top of the corset, particularly if the arms are raised above the head, and when they do so, they cannot well be replaced without undressing. By the means provided by the present invention this objection is avoided.

In the accompanying drawings, Fig. 1 is a perspective view of the brassière. Fig. 2 is a plan view. Fig. 3 is a plan of a modification.

The brassière shown in Figs. 1 and 2 consists of two similar sections, 6 and 7, made of suitable fabric and shaped to conform to the bust of a wearer. Each section is provided with stays or stiffeners 8 under the arm, and with a shoulder strap 9, and at the back with lacing eyelets 10, so that when in use the device can be laced up the back and thereby roughly adjusted. And the laces 11 permit the device to be opened or separated so that it can be slipped on over the head, the ends of the laces being then brought around and tied in front as indicated. This permits the brassière to be very quickly put on or taken off and adjusted for use.

The front end of each section has a strap or tongue 13 which overlaps the front portion of the other section and extends around to the side or back, the outer tongue 13 being connected to a tab 14 by laces 15, and the inner or under tongue being connected to a tab 16 by laces 17, extending through a slit at 18 in the under arm portion of the opposite section. This slit permits the tongue 13 to be brought through to the outside of the section. The laces 15 and 17 enable the brassière to be drawn tightly around the figure under the bust, and will hold it down in place. At the front, the under section has a small strap 19 attached thereto and extending through a loop 20 on the inner side of the outer section, and this

strap terminates in a hook 21 which may be hooked into the corset strings to assist in holding the front of the brassière down in place. The two sections are fastened together at the front upper edge by stitching indicated at 22. The upper edges of the tongues 13 are curved downwardly so that they will extend or be located under the largest part of the bust, and there is only one thickness over the upper part of the bust.

In the modified form shown in Fig. 3 the construction is the same, except that instead of passing one of the tongues 13 through a slit in the other section, one tongue 13^a is laced to a tab on the outside, as shown at 13^a, and the other tongue 13^b is laced as at 13^b to a tab on the inside of the other section. When these laces are once adjusted they can be tied to remain at adjustment so that the brassière will always fit, the brassière being taken up by the back laces 11 in the manner described.

The whole forms a very convenient and easily applied article having manifest advantages with respect to the means for adjusting and holding it in position.

I claim:

1. A brassière comprising two side sections fastened together at their top front edges and connected by lacing at the back, each section having a laterally extending tongue which laps the other section and is adjustably connected to the latter on the outer side thereof and near the lower edge thereof.

2. A brassière comprising two side sections fastened together at their top front edges and connected by lacing at the back, each section having a laterally extending tongue which laps the other section and is adjustably connected thereto, and a strap provided with a hook attached to the lower end of one section and extending downwardly through a loop on the other section.

In testimony whereof, I affix my signature.

CHRISTINE PETERSEN.
